Primary Examiner — Cynthia Ramirez*(74) Attorney, Agent, or Firm* — The Webb Law Firm(57) **CLAIM**

The ornamental design for a lifting device for vehicle, as shown and described.

DESCRIPTION

FIG. 1 is an upper front perspective view of a lifting device for vehicle, showing my new design;

FIG. 2 is a lower rear perspective view thereof;

FIG. 3 is a rear elevation view thereof;

FIG. 4 is a front elevation view thereof;

FIG. 5 is a top view thereof;

FIG. 6 is a bottom view thereof;

FIG. 7 is a right side elevation view thereof; and,

FIG. 8 is a left side elevation view thereof.

The portions of the lifting device for vehicle shown in broken lines form no part of the claimed design.

1 Claim, 8 Drawing Sheets(56)
